UNITED STATES PATENT OFFICE.

OTTO HOGE, OF GREAT FALLS, MONTANA.

ATTACHMENT FOR WASHBOILERS.

Application filed October 15, 1924. Serial No. 743,799.

This invention contemplates the provision of a device designed to accommodate itself within a tank or other suitable receptacle, in which clothes, dishes or other articles are adapted to be washed, and by means of which the said articles can be elevated above the fluid in said tank and allowed to drain.

More specifically stated, the invention is in the nature of an attachment for such tank or receptacle, and embodies a foraminated container adapted to be submerged in the water in said tank, the container being associated with means whereby it can be elevated, and supported in an elevated position to allow the articles therein to drain.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view showing the tank in section and the manner in which the foraminated container is held elevated therein.

Figure 2 is a view taken at a right angle to Figure 1.

Figure 3 is a perspective view of the holder for said container.

Figure 4 is a fragmentary perspective view of the clamp and its associated parts.

Before entering into a detail description of what is herein shown, I desire to have it understood that while the invention is primarily intended to be used for draining clothes, dishes or the like, that it can be used for various other analogous purposes, and that its general application is contemplated by the claim.

The device forming the subject matter of this invention includes a foraminated receptacle 10 which may be constructed of wire of any suitable mesh, or from any other suitable material having its sides and bottoms perforated. The receptacle 10 is adapted to be arranged in a holder, preferably of the construction illustrated in Figure 3, although the holder in itself may vary in size and design without departing from the spirit of the invention. As herein illustrated, the holder is made up of two identi-

cally constructed sections, each including a base 11 from one end of which rises an arm 12 while projecting from the opposed longitudinal edges of the base are extensions 13 which also terminate to provide vertically disposed arms 14. The base members 11 of the respective sections are overlapped as shown in Figure 3, one of which is formed with a longitudinal slot 15 to receive a headed bolt 16 which passes through an opening in the base member of the other section, whereby the length of the holder may be varied to accommodate different size containers, and also to accommodate itself to tanks of different size, with which the invention is intended to be used. It will be noted upon inspection of Figure 3 that the arms of each section are grouped and arranged to engage the side and end walls of the container 10, and are preferably of a height equal to the height of said container. This structure in its entirety is adapted to be placed in a tank 17, such as a wash boiler or the like, and the articles to be washed with in said tank are of course placed within the container 10, which receives the water or other fluid with which the tank is partly filled. After the articles have been properly dealt with, it is my purpose to provide means whereby the container 10 can be elevated within the tank 17 to a position above the water level, and supported in this position to allow the articles therein to properly drain.

For this purpose I make use of a cable 18 which passes beneath the base of the container holder, and trained over guide pulleys 19 journaled at the ends of said base as shown. One end of this cable is attached to the adjacent end of a duplex hook like element 20, the other end of which is adapted to be suspended from the top of the tank as shown in Figure 1. The other end of the cable is attached to a drum 21 and adapted to be wound about and unwound therefrom to raise and lower the container 10 with relation to the tank 17. This drum is fixed on a shaft 22 which is journaled in a clamp 23 the latter being preferably of U-shape formation but having its spaced limbs connected at an appropriate point in their length by a cross piece 24 which is adapted to repose upon the upper edge of the tank when the clamp is associated therewith. One of these limbs carries a tightening screw 25, which is

adapted to engage the tank to hold the clamp fixed relatively thereto. The shaft 22 is equipped with a crank handle 26 through the instrumentality of which the shaft can be rotated. Also fixed to the shaft 22 is a ratchet wheel 27, while pivoted upon the clamp as at 28 is a pawl 29 designed to cooperate with the ratchet wheel 27 to prevent retrograde movement of the shaft as will be readily understood. Manifestly by reason of this construction it will be noted that when the shaft is turned in one direction and the cable 18 wound about the drum 21, the container will be elevated within the tank 17, and the pawl and ratchet mechanism utilized to support the container in this position to allow the articles therein to drain. In order to lower the container within the tank, it is only necessary to throw the pawl 29 to an inactive position, that is out of engagement from the ratchet 27, whereupon the container will gravitate within the tank incidentally unwinding the cable from the drum 21.

For the purpose of guiding and steady-
ing the container while being elevated or lowered with relation to the tank 17, I pro-
vide one of the arms of the holder with a
longitudinal slot 30, this arm being ar-
ranged in juxtaposition with the clamp 23,
so that the pin 31 projecting from said

clamp will be received by the slot. The de-
vice in its entirety is as above stated in the
nature of an attachment which can be
quickly and conveniently associated with
any tank of a size and shape to accommo-
date the container, and used advan-
tageously for the purposes enumerated.

While it is believed that from the fore-
going description, the nature and advan-
tages of the invention will be readily ap-
parent, I desire to have it understood that
I do not limit myself to what is herein
shown and described, and that such changes
may be resorted to when desired as fall
within the scope of what is claimed.

What I claim is:

A receptacle holder of the character de-
scribed comprising two identically con-
structed sections, each including a base, an
arm rising from the outer end thereof, ex-
tensions projecting from the opposite sides
of the base, arms rising from said extensions
and arranged in right angular relation to
the first mentioned arms, the base portions
of the respective sections being overlapped
and slidably associated, and a keyhole slot
in the first mentioned arm of one of said
sections.

In testimony whereof I affix my signa-
ture.

OTTO HOGE.
